(57) **CLAIM**

I claim the ornamental design for a pourable colander, as
shown and described.

DESCRIPTION

FIG. 1 is a perspective view of the pourable colander according
to the present invention.

FIG. 2 is a top plan view of the colander.

FIG. 3 is a front elevation view of the colander.

FIG. 4 is a right side elevation view of the colander, with the
left side being a minor image of the right side.

FIG. 5 is a back elevation view of the colander; and,

FIG. 6 is a bottom plan view of the colander.

Applicant makes no claim to the structure shown in broken
lines (the drainage openings) in the drawings.
